Montgomery Patent & Design LP(57) **CLAIM**

The ornamental design for a set of panty hose, as shown and described.

DESCRIPTION

FIG. 1 is a perspective front view of a set of panty hose, including a first leg portion, a second leg portion, and a third leg portion, showing my new design;

FIG. 2 is a front side view thereof;

FIG. 3 is a back side view thereof;

FIG. 4 is a left side view thereof;

FIG. 5 is a right side view thereof;

FIG. 6 is a top side view thereof; and,

FIG. 7 is a bottom side view thereof.

The dashed lines indicate boundary areas and form no part of the claimed design.
